US0D1079169S

(12) **United States Design Patent** (10) **Patent No.:** **US D1,079,169 S**
(45) **Date of Patent:** **** Jun. 10, 2025**

(54) **SCRAPER HEAD**

(71) Applicant: **HONG ANN TOOL INDUSTRIES CO., LTD.**, Taichung (TW)

(72) Inventor: **Cheng-Wei Su**, Taichung (TW)

(73) Assignee: **HONG ANN TOOL INDUSTRIES CO., LTD.**, Taichung (TW)

(**) Term: **15 Years**

(21) Appl. No.: **29/861,307**

(22) Filed: **Nov. 29, 2022**

(51) LOC (15) Cl. **07-05**

(52) U.S. Cl.

USPC **D32/46**

(57) **CLAIM**

The ornamental design for a scraper head as shown and described.

DESCRIPTION

FIG. 1 is a perspective view of a scraper head showing my new design;

FIG. 2 is a front view thereof;

FIG. 3 is a rear view thereof;

FIG. 4 is a left view thereof;

FIG. 5 is a top view thereof;

FIG. 6 is a bottom view thereof; and,

FIG. 7 is another perspective view thereof showing a using condition with a blade.

The broken lines depict portions of the scraper head that form no part of the claimed design.

1 Claim, 7 Drawing Sheets
